WASHING APPARATUS

Filed May 14, 1929

BY HIS ATTORNEYS: - *Howard L. Ward*

UNITED STATES PATENT OFFICE

FREDERICK HILL, OF URMSTON, ENGLAND

WASHING APPARATUS

Application filed May 14, 1929, Serial No. 363,064, and in Great Britain May 16, 1928.

This invention of improvements in apparatus for use in washing animal offals and for other analogous purposes relates specially to apparatus for washing tripe, animal feet and other animal offals and is applicable also in apparatus for other analogous purposes as, for example, for washing roots.

The invention provides an apparatus in which the washing liquid is made to flow in one direction and the material to be washed is made to pass through the apparatus in a contrary direction by the action of persons handling or working the material in the washing thereof so that the material is washed progressively in cleaner water and lastly in clean water and the dirt or other matter washed off or from the material is carried out of the apparatus with the waste water so that there is no or little accumulation of dirt or waste matter in the apparatus.

This invention consists in a washing apparatus comprising a tank presenting a channel for the flow of water and provided at one end with a pipe or pipes or other means for the supply of water and if desirable a pipe or pipes for the supply of steam or other means for heating water supplied, if heating be desirable or necessary, and provided at the other end with an outlet weir or overflow opening or passage employed or contrived with a baffle or counterplate or formed as a pipe or pipes or channel or channels with the entrance or entrances at the lower end and the outlet or outlets at a higher level or made to rise from the entrance or entrances and to descend to an outlet or outlets at or above the level of the entrance or entrances or otherwise for water to pass to it from near the bottom of the tank so that while the water flowing through the tank shall be kept in a stream of approximately constant depth the water flowing from the tank shall carry out with it all or nearly all the dirt or matter washed off or out of the material.

The material to be washed may be placed or supplied by hand or otherwise in or to the tank at one end thereof and the washed material may be removed at the other end of the tank by hand or in any other manner.

A washing apparatus provided according

to the invention in a form to be described as an illustrative embodiment, is illustrated in the accompanying drawing in which Fig. 1 is a side elevation of the apparatus and Fig. 2 is a plan thereof. Fig. 3 is a vertical section taken approximately on the plane indicated by the line 3—3 of Fig. 2 and Fig. 4 is a vertical section taken approximately on the plane indicated by the line 4—4 of Fig. 2. Fig. 5 is a vertical transverse section on a larger scale than Figs. 3 and 4 showing the formation of the upper edges of the apparatus.

The same numerals of reference are employed to indicate corresponding parts in all the figures.

The washing apparatus shown in Figs. 1, 2, 3 and 4 of the drawing, comprises a tank 6 divided for the greater part of its length by a partition 7 into two compartments or limbs 8 and 9, each closed at one end and communicating by and only by their other ends in a part of the tank bounded by a wall 10 curved approximately in a semi-circle. The one compartment or limb 8 at or near its closed end is furnished with, as shown, a pipe 11 or if desirable with two or more such pipes, for the supply of water or it may be supplied otherwise with running water and, if heating be desirable or necessary, furnished with a pipe for the supply of steam or other means for heating the water supplied. The closed end of the other compartment or limb 9 is furnished with an outlet 12 for water and with a mid-feather or partition 13 extending across it and nearly to the bottom of the tank 6 and with another mid-feather or wall or partition 14 extending from the bottom upwards to near the top of the tank 6 to divide the interior of the tank 6 from the outlet 12. The outlet 12 for water is shown as a straight channel or passage extending across and below the compartment or limb 9 and bounded in part by the end and one side thereof, and the mid-feather or partition 7 and in part by the mid-feather or wall or partition 14 which parts are all made to extend or provided with parts extending down to the lower end of the outlet channel 12. The walls and bottom of the tank 6, the partition 7, the mid-feather

or partition 13 and mid-feather or wall 14 are all shown as formed of metal sheet or plate and riveted together and to a framework 17 further to be described herein.

- 5 Beads or rims 15 of sheet metal folded or curled upon itself, as shown best in Fig. 5 are shown as applied on and secured as by riveting on the upper edges of the wall of the tank 6, the partition 7 and the mid-feather or partition 13 in order to obviate risk of injury to the wet and tender hands and arms of operators working with the apparatus. 16 is a stay secured as by riveting to the partition 7 at the end nearest the rounded end of the tank 6 and to the wall of the tank 6 at the sides in order to secure the partition 7 against bending or strain. The stay 16 is made to present a semi-circular transverse section or rounded upper surface so as to obviate risk 20 of injury to the wet and soft hands and arms of operators.

The frame-work 17 serving to support and stiffen the walls and bottom of the tank 6 by being riveted thereto and to form legs or feet 25 is shown as formed of angle plates which in the case of the two nearer the rounded end of the tank 6, are divided along part of the angle so that each is made to present one arm to extend up the side of the tank 6 and another 30 arm which is bent to extend across beneath the bottom of the tank 6. Around a hole 18 in the bottom of the compartment or limb 8 of the tank 6, an annular internally screw-threaded collar 19 is secured to receive a 35 screw-threaded plug 20 which is ordinarily made to close the hole 18 but may be removed when requisite for the tank 6 to be cleaned. Preferably the tank 6 is galvanized when fully constructed.

40 In the use of the apparatus shown, four operators usually work with the tank 6, standing approximately at the places indicated by the numerals 21, 22, 23, 24, and work in succession in the order of those numerals 45 with the animal offal or other material to be washed.

Water being made to flow through the tank 6 from the inlet 11 to the outlet 12 and heated if necessary or desirable, the animal offal or other material to be washed is introduced into the one compartment or limb 9 of the tank 6 near the outlet 12 for water and by the introduction of fresh material and by the action of persons handling or working the material in the washing thereof, the material is passed gradually first along that compartment or limb 9 and then into the other, 8, and eventually to the end at which that other limb or compartment 8 is supplied with water and so as it becomes cleaner it is washed with gradually cleaner and finally with clean water while all or nearly all the dirt or other matter removed from the material washed, is carried out of the tank 6 with the out-flowing water.

In Fig. 2 the arrows 25 drawn in solid lines indicate the direction of the flow of the water and the arrows 26 shown in dotted lines indicate the direction in which the material being washed is made to pass along the tank 6.

Obviously there is opportunity for variation of detail in the construction of washing apparatus according to this invention, as for example, in particular, the provision or omission of pipes for the supply of steam or 75 hot water.

What I do claim as my invention and desire to secure by Letters Patent is:

1. A washing apparatus for the purpose indicated comprising, a tank completely open and unobstructed above and free of internal moving parts, which tank is surrounded by a wall curved in part approximately in a semicircle to form one end of the tank and is divided for the greater part of its length 80 by a partition extending upwards from the bottom and from the other end towards the curved part of the wall into two limbs each closed at one end and communicating only by their other ends in the part of the tank bounded by the curved part of the wall, thereby constituting a channel completely open and unobstructed throughout its length above, internally unobstructed throughout 85 its length from the closed end of one limb to the closed end of the other, relatively long in proportion to its width, and of adequate length to present a series of working places continuous one with another and freely accessible in which material may be washed 90 progressively in successive stages in passage from the end of one limb to the end of the other limb; means for the supply of running water at the end of the limb from which material washed is removed, and an overflow 95 outlet passage at the end of the other limb where material to be washed is introduced, which overflow outlet passage has its entrance near the bottom of said tank.

2. A washing apparatus for the purpose indicated comprising, a tank completely open and unobstructed above and free of internal moving parts, which tank is surrounded by a wall curved in part approximately in a semicircle to form one end of the tank and is divided for the greater part of its length 100 by a partition extending upwards from the bottom and from the other end towards the curved part of the wall into two limbs each closed at one end and communicating only by their other ends in the part of the tank bounded by the curved part of the wall, thereby constituting a channel completely 105 open and unobstructed throughout its length above, internally unobstructed throughout its length from the closed end of one limb to the closed end of the other, relatively long in proportion to its width, and of adequate 110 length to present a series of working places continuous one with another and freely accessible in which material may be washed progressively in successive stages in passage from the end of one limb to the end of the other limb; means for the supply of running water at the end of the limb from which material washed is removed, and an overflow outlet passage at the end of the other limb where material to be washed is introduced, which overflow outlet passage has its entrance near the bottom of said tank.

accessible in which material may be washed progressively in successive stages in passage from the end of one limb to the end of the other limb; means for the supply of running water at the end of the limb from which material washed is removed, a baffle extending across and to a point near the bottom of said channel at the end of the limb where material to be washed is introduced, and an overflow-weir at the side of said baffle remote from said channel, said baffle and overflow-weir providing an overflow outlet passage which has its entrance near the bottom of the tank.

15 3. A washing apparatus for the purpose indicated comprising, a tank completely open and unobstructed above and free of internal moving parts, which tank is surrounded by a wall curved in part approximately in a semicircle to form one end of the tank and is divided for the greater part of its length by a partition extending upwards from the bottom and from the other end towards the curved part of the wall into two limbs each closed at one end and communicating only by their other ends in the part of the tank bounded by the curved part of the wall, thereby constituting a channel completely open and unobstructed throughout its length above, internally unobstructed throughout its length from the closed end of one limb to the closed end of the other, relatively long in proportion to its width, and of adequate length to present a series of working places continues one with another and freely accessible in which material may be washed progressively in successive stages in passage from the end of one limb to the end of the other limb; an inlet pipe in one limb for the supply of running water and an overflow outlet passage at the end of the other limb where material to be washed is introduced, which overflow outlet passage has its entrance near the bottom of said tank.

4. A washing apparatus for the purpose indicated comprising, a tank completely open and unobstructed above and free of internal moving parts, which tank is surrounded by a wall curved in part approximately in a semicircle to form one end of the tank and is divided for the greater part of its length by a partition extending upwards from the bottom and from the other end towards the curved part of the wall into two limbs each closed at one end and communicating only by their other ends in the part of the tank bounded by the curved part of the wall, thereby constituting a channel completely open and unobstructed throughout its length above, internally unobstructed throughout its length from the closed end of one limb to the closed end of the other, relatively long in proportion to its width, and of adequate length to present a series of working places

continuous one with another and freely accessible in which material may be washed progressively in successive stages in passage from the end of one limb to the end of the other limb; an inlet pipe for the supply of running water; a baffle extending across and to a point near the bottom of said channel at the end of the limb where material to be washed is introduced, and an overflow-weir at the side of said baffle remote from said channel, said baffle and overflow-weir providing an overflow outlet passage which has its entrance near the bottom of the tank.

In testimony, that I claim the foregoing as my invention, I have signed my name this third day of May, 1929.

FREDERICK HILL.
